[57] **CLAIM**

The ornamental design for a tree drain grate or similar
article, substantially as shown and described.

DESCRIPTION

FIG. 1 is a top perspective view of a tree drain grate or
similar article showing my new design;

FIG. 2 is a side elevation view thereof;

FIG. 3 is a top plan view thereof;

FIG. 4 is a top perspective view of a second embodiment
thereof;

FIG. 5 is a top perspective view of a third embodiment
thereof; and

FIG. 6 is a top perspective view of a fourth embodiment
thereof.

Portions of FIGS. 3-6 are shown in broken lines for
ease of illustration and are understood to be identical to
the portions shown in full lines.
